Primary Examiner — Katherine Glennon(74) *Attorney, Agent, or Firm* — Taft Stettinius & Hollister LLP(57) **CLAIM**

The ornamental design for a watch case, as shown and described.

DESCRIPTION

FIG. 1 is a front elevational view of a watch case showing my new design;

FIG. 2 is a back elevational view thereof;

FIG. 3 is a bottom plan view thereof;

FIG. 4 is a top plan view thereof;

FIG. 5 is a right side elevational view thereof;

FIG. 6 is a left side elevational thereof;

FIG. 7 is a front, bottom, right side perspective view thereof; and,

FIG. 8 is a back, top, right side perspective view thereof. The broken lines in the drawing figures depict portions of the watch case that form no part of the claimed design.

1 Claim, 6 Drawing Sheets(56)
